UNITED STATES PATENT OFFICE.

AUGUSTE BARON, OF ASNIÈRES, FRANCE.

APPARATUS FOR TAKING AND REPRODUCING ANIMATED SCENES AND SOUNDS.

SPECIFICATION forming part of Letters Patent No. 656,762, dated August 28, 1900.

Application filed October 31, 1898. Serial No. 695,024. (No model.)

To all whom it may concern:

Be it known that I, AUGUSTE BARON, photographer, a citizen of the French Republic, residing at 10 Rue de l'Alma, in the city of 5 Asnières, Seine, France, have invented Improved Apparatus for Taking and Reproducing Animated Scenes and Sounds, of which the following is a full, clear, and exact description.

10 This invention relates to an apparatus for recording animated scenes and their accompanying sounds simultaneously and for reproducing the same simultaneously. The apparatus consists of two distinct parts which 15 are so combined as to mutually contribute to the obtainment of the above-mentioned result. One part consists of a photographic apparatus for taking a series of photographs of the same moving subject at very rapid intervals, while the other part consists of a phonograph for recording the sounds accompanying the motions of the subject during the operation of the photographic apparatus. The 20 phonographic apparatus is connected to the photographic apparatus by an electrical apparatus whose movement is controlled by the driving-wheel of said photographic apparatus in such manner as to cause the two apparatuses to move together at the same speed, and 25 during the reproduction by projection of the subject photographed the movements will be represented synchronously with the accompanying sounds, so that the spectators will both see the scenes and hear the sounds 30 produced exactly as in reality. An apparatus in which my invention is embodied is shown by way of example in the accompanying drawings, in which—

Figure 1 is a front elevation of both the 40 phonographic and photographic apparatuses, these two apparatuses being electrically connected by wires. Fig. 2 is a plan view of the motor of the phonograph. This view likewise shows the circuits and the commutator for 45 controlling the motor. Fig. 3 is an enlarged detail sectional elevation of the phonograph, and Fig. 4 is a detail view of the commutator.

The photographic apparatus or camera, by 50 which I mean to also include a picture-projector, is mounted upon an iron frame, which supports a wood casing inclosing the whole of

the mechanism and varying in dimensions according to the size of the photographs.

As shown in Fig. 1, N is a removable magazine in which is contained the spool of film, 55 whether sensitized or covered with positive pictures, according as the apparatus is used for taking or projecting the scenes. The magazine has a slide N^b, which is drawn out when the magazine has been mounted on the apparatus. The film-spool turns freely upon a spindle N^a, which is mounted in the sides of the magazine N.

The fly-wheel A H, Fig. 1, which is rotated by hand or by an independent motor, drives 60 the camera or kinetoscope.

The second part of the apparatus consists of a phonograph whose movement is synchronized or harmonized with that of the photographic apparatus by the following arrangement of mechanism: a, Fig. 1, indicates a group of battery-cells for the supply of the current by means of wire b to a commutator consisting of a copper ring c, Fig. 4, screwed on the side of the casing of the photographic apparatus, Fig. 1. To this ring c, Fig. 1, is fixed an ebonite sleeve d, containing a cylinder e, also of ebonite, (see Fig. 2,) which carries a copper ring f, against which constantly bears the contact g, connected to binding-screw h, Fig. 2, which traverses sleeve d. The ring f has an extension longitudinal of the ebonite cylinder e, which latter is fast on the spindle i, which passes through it and partakes of the rotary motion imparted to pinion 70 j by the teeth on driving-wheel M, Fig. 4, of the photographic apparatus. During this movement the extension on ring f comes successively in frictional contact with the contacts connected to the sockets of terminals h 75 k l by flexible strips, so that the current which is constantly supplied at terminal g to ring f is distributed successively to the electromagnets m n o, Fig. 2, in correspondence with the speed imparted to the driving-wheel M. The 80 electromagnets m n o, Figs. 2 and 3, are preferably six in number and are placed in pairs around the circumference of an armature p, bearing studs q, (eight in number,) which are successively attracted by the poles r of the 85 electromagnets. The current supplied by the commutator passes alternately by the wires

90 k l by flexible strips, so that the current which is constantly supplied at terminal g to ring f is distributed successively to the electromagnets m n o, Fig. 2, in correspondence with the speed imparted to the driving-wheel M. The 95 electromagnets m n o, Figs. 2 and 3, are preferably six in number and are placed in pairs around the circumference of an armature p, bearing studs q, (eight in number,) which are successively attracted by the poles r of the 100 electromagnets. The current supplied by the commutator passes alternately by the wires

s t u to the electromagnets *m n o*, which in turn attract the studs of armature *p*, and by means of springs *v* transmit the circular motion thus obtained to the fly-wheel *w*, mounted on shaft *x*. The object of the springs *v* is to counteract the jerks which may be produced by the successive attractions of armature *p*. The current on its exit from the electromagnets is returned to the battery by the return-wire *y*. (See Fig. 1.)

The entire electric mechanism hereinbefore described is contained within the phonograph-casing *z*, Fig. 3. The shaft *x* projects up through the top of said casing and upon its upper end is keyed a bevel-toothed wheel *a'*, which gears with two other similar wheels *b'* and *c'*, of which wheel *b'* imparts rotary motion to the phonographic cylinder *e'*, while the wheel *c'* imparts a forward movement to the diaphragm-carrier *f'*. The wheel *b'* is fast on the axis on which is mounted the sleeve which carries the phonographic cylinder *e'*, the said wheel and its shaft being made removable to permit of inserting and changing the phonographic cylinders. A small pivoted latch *f''*, engaging in a notch in a ring *g'*, formed on wheel *b'*, serves to insure the correct register of the cylinders at the moment of starting the apparatus. The wheel *c'* is fast on a leading screw *h'*, with which engages a nut *j'*, which is connected by means of a bar to the diaphragm-carrier *f'*, the outer end of said screw *h'* being supported in a bracket *k'*, Fig. 1, so that when screw *h'* commences to be rotated by wheel *c'* it forces the nut *j'* to advance, thus carrying with it the diaphragm-carrier *f'*. At *l'* is shown the vibrating diaphragm carrying its stylus, and *m'*, Fig. 3, is the sound-tube connected to the horn *o'* to amplify the sounds emitted by the diaphragm and project them toward the audience. When an operation is finished and it is desired to return to the starting-point, it is simply necessary to rock the diaphragm-carrier about its guiding-axis *n'*, Fig. 3, so as to disengage nut *j'* from screw *h'* and then slide the whole backward upon the guide or axis *n'*.

From the foregoing description the action of the apparatus in the two cases of taking and projecting views will be easily understood. On commencing to turn the driving-wheel *M* the commutator causes the current

to pass successively to the electromagnets, the phonographic cylinder is rotated at a speed which is absolutely synchronous or 55 harmonious with that of fly-wheel *A H*, and the tube or horn being turned toward the scene to be photographed the phonographic cylinder records the sounds emitted at same time that the cinematograph records the corresponding movements. For projecting the views the positive film, produced in the ordinary way from the negative film previously obtained, is then placed in the apparatus, the first picture occupying the same position as 60 the first negative, and the phonographic cylinder replaced in its support and the diaphragm-carrier returned to the starting position. It is now only necessary to turn the fly-wheel *A H* in order to impart to both apparatuses an absolutely-synchronous movement, and thus obtain a simultaneous reproduction of the movements and sounds previously recorded.

It is to be understood that the forms, dimensions, details, and materials employed in the construction of the apparatus may be varied without in any way changing the principle of the invention and that the word "camera" is intended to include also a projector or 70 kinetoscope.

Having described my invention, what I claim, and desire to secure by Letters Patent, is—

In an apparatus for recording or exhibiting 85 simultaneously-occurring visible and audible effects, the combination of a phonograph with electrical means for driving the same, a kinetographic camera, a current-distributing commutator operated by the kinetographic camera apparatus and circuit connections intervening between the current-distributing commutator and the electrical means for driving the phonograph so as to effect the operation of the phonograph in synchronism with the 90 95 kinetographic camera.

The foregoing specification of my improved apparatus for taking and reproducing animated scenes and sounds signed by me this 17th day of October, 1898.

AUGUSTE BARON.
